UNITED STATES PATENT OFFICE.

LEWIS G. WARD, OF WILLIAM, WEST VIRGINIA.

BELT-CUTTING MACHINE.

1,092,547.

Specification of Letters Patent.

Patented Apr. 7, 1914.

Application filed November 18, 1911. Serial No. 660,981.

To all whom it may concern:

Be it known that I, LEWIS G. WARD, a citizen of the United States, residing at William, in the county of Tucker, State of West Virginia, have invented certain new and useful Improvements in Belt-Cutting Machines; and I do hereby declare the following to be a full, clear, and exact description of the invention, such as will enable others skilled in the art to which it appertains to make and use the same.

This invention relates to belt cutting machines.

The object of the invention resides in the provision of a belt cutting machine which is adapted in a single operation to square the end of a belt and punch holes therein a suitable distance from the end for the reception of fastening devices whereby the ends of the belt may be readily laced together to form a continuous member.

A further object of the invention resides in the provision of a belt cutting machine which includes a base and a cutting mechanism carried thereby adapted to be adjusted longitudinally of the base and operated in any adjusted position.

A still further object of the invention resides in the provision of a belt cutting machine which includes a base, a cutting mechanism supported upon the base and means for holding a belt upon the base beneath the cutting mechanism, said belt holding means being adjustable longitudinally of the base and relatively to the cutting mechanism.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a plan view of the invention; Fig. 2, a side elevation thereof; Fig. 3, a view similar to Fig. 2 looking at the opposite side of the device; Fig. 4, an end view of the invention; Fig. 5, a section taken on the line 5—5 of Fig. 1; Fig. 6, a section taken on the line 6—6 of Fig. 1, and Figs. 7, 8 and 9 are detail perspective views illustrating the various forms of tools employed

in addition to the cutting blade which trims and squares the end of the belt.

Referring to the drawings the machine is shown as comprising a base 10 the upper side of which has embedded therein a bed plate 11. Secured to one side edge of the base 10 are inner and outer bars 12 and 13 respectively, the end of the bar 13 terminating short of the ends of the base 10. The upper ends of adjacent faces of the bars 12 and 13 are curved outwardly to produce a longitudinally extending cutting groove 14 for coöperation with a cutting blade to be hereinafter referred to.

Disposed at each end of the base 10 are vertical standards 16 and 17 each of which is shown as comprising three separate plates connected together side to side. The lower end of the central plate of each of the standards 16 and 17 terminates short of the lower ends of the limiting plates of said standards thereby forming a space between the limiting plates which receives the bar 12. The lower end of the outer limiting plates of the standards 16 and 17 are bent outwardly as at 18 and 19. Mounted on the outwardly bent lower end 19 is a lug 20 in which is slidably mounted the spring bolt 21 which engages through registering openings in the limiting plates of the standard 17 and the bar 12 to secure said standard to the bar 12. A lag bolt 22 is engaged through the limiting plates of the standard 16 and through the bar 12 to likewise secure said standard 16 to the bar 12. The standards 16 and 17 are connected to the adjacent ends of the base 10 by means of braces 23 and 24 respectively, said braces being detachably engaged to the base and standards so that by disengagement of same and the disengagement of the lag bolt 22 and spring bolt 21 the standards 16 and 17 may be readily removed from the bar 12.

Secured to the outer sides of the standards are spaced parallel plates 24', while another plate 25 corresponding in position to the uppermost plate 24' is secured against the inner sides of the standards 16 and 17. Disposed between the plates 24' and 25 is a head A which includes vertical members 26 and 27 each of which is formed of three separate plates secured together side to side. The upper ends of the members 26 and 27 are connected by parallel spaced plates 28 and 29.

Slidably mounted in the head A is a cutting mechanism B which includes a U-shaped plate 30 the free ends of the arms of which are connected by parallel plates 31 and 32. Secured to the lower end of the U-shaped plate 30 is a cutter 33 which during the operation of the cutting mechanism moves into and out of the groove 14. Pivotally mounted between the plates 28 and 29 is a cam lever 34 which has mounted therein a transverse pin 35 adapted to coöperate with the walls of recesses 36 formed in the lower edges of the plates 31 and 32. The cam end of the lever 34 is so shaped and positioned that when the free end of said lever is depressed said cam end will coöperate with the inner edge of the portion of the U-shaped plate 30 which connects the arms of said plate so as to force the plate downwardly and impart the cutting stroke to the cutter 33. When the free end of the lever 34 is elevated the pin 35 will coöperate with the walls of the recesses 36 so as to lift the plate 30 and cutter 33. Disposed against the outer faces of the plates 24' are bars 37, while bars 38 are disposed against the outer face of the plate 25. These bars 37 and 38 are connected respectively to the members 26 and 27 by means of bolts 39. By this construction it will be apparent that the head A and cutting mechanism B are slidably supported above the base 10 by the plates 24' and 25 so that said head and cutting mechanism can be adjusted longitudinally of the base as will be obvious.

Secured to the end of the head A adjacent the standard 16 is a pivoted latch 40 provided with recesses 41 adapted to engage over the upper end of the standard 16 so as to lock the head A and cutting mechanism B in different adjustments.

The side of the base 10 remote from the bar 12 is provided with a groove 42 in which is slidably mounted a bar 43 formed of a pair of sections arranged side to side. The end of this bar 43 adjacent the standard 17 is provided with a lateral extension 44 upon which is mounted a plate 45 which partially rests upon the top of the base 10 and disposed at right angles to the cutter 33. The outer edge of the plate 45 is provided with a recess 46 in which is engaged the right portion of a U-shaped plate 47. The lower arm of this U-shaped plate 47 is suitably secured to the lateral extension 44, while the upper arm of said plate is bifurcated and has pivoted thereon a clamping lever 48 for coöperation with the lower arm of said plate.

Projecting laterally from the standards 16 and 17 are rods 49 and 50 respectively. Journalled on the rod 49 is a lever 51 while an arm 52 is journalled on the rod 50. A clamping link 53 has one end pivotally connected to the free end of the arm 52

and its other end pivotally connected to one end of the lever 51. By this construction it will be apparent that upon operating the lever 51 the clamping link 53 may be moved toward and away from the base 10, the movement of said link toward the base serving to clamp a belt disposed upon the base against movement. In this connection it will also be noted that when a belt is disposed upon the base 10 it will lie between the arms of the plate 47 so that the lever 48 can be operated to clamp the belt to the plate 47. When a belt is so clamped the link 53 may be released and the belt adjusted longitudinally of the base 10 by sliding the bar 43 in the groove 42. After the belt is properly adjusted by this means the link 53 is returned to clamping position for the institution of a cutting operation.

Projecting laterally from the plate 30 in the same horizontal plane are studs 54 over which are adapted to be engaged different forms of tools such as are shown in Fig. 7. Also projecting laterally from the plate 30 above each of the studs 54 are studs 55 in which latter are mounted respectively binding screws 56 through the instrumentality of which the tools mounted on the studs 54 are locked against disengagement from the latter. An angle bracket 57 is secured to the inner side of the standard 16 for adjustment longitudinally of the base. One arm of this bracket extends transversely of the base and is adapted to coöperate with the plate 45 in squaring the work placed upon the base 10.

The bed plate 11 is provided with a plurality of slots 58 which are adapted to coöperate with the knives of the tool 59 for the purpose of forming slits in the belt at the same time the edge of the belt is trimmed by the cutter, such slits being adapted to receive the lacing usually employed in securing the ends of the belt together. The bed plate 11 is also provided with a boss 60 which is adapted to coöperate with the tool 61 for the purpose of making a small opening through the belt without taking any material from the latter. The tool indicated at 62 is adapted to be used for punching a series of holes in the belt for mounting lacing eyes, this tool being operated simultaneously with the cutter as will be obvious.

What I claim is:

1. In a belt cutting machine the combination of a base, a head mounted on said base, a cutter carrier mounted for vertical movement in said head, said carrier comprising spaced arms mutually connected at their lower ends, parallel plates connecting the upper ends of said arms a lever pivoted on said head and extending between said parallel plates, a cam face on the inner end of said lever adapted when the lever is moved in one direction to coöperate with the inner edge of said mutual connection to force the

cutter carrier downwardly, and a transverse pin carried by said lever coöperating with the walls of recesses formed in the lower edges of said parallel arms when the lever is moved in the opposite direction to elevate said cutter carrier.

2. In a belt cutting machine the combination of a base, a cutting mechanism mounted on said base for adjustment longitudinally thereof, means for squaring the work on the base with respect to the cutting mechanism, a pair of rods extending transversely of the base, a lever pivoted on one of said rods an

arm pivoted on the other rod, and a link having one end pivotally connected with 15 said arm and its other arm pivotally connected with said lever whereby the oscillation of said lever will move said link to and from the base in substantial parallelism to the latter.

In testimony whereof, I affix my signature, in presence of two witnesses.

LEWIS G. WARD.
